UNITED STATES PATENT OFFICE.

PAUL H. ZIMMER, OF MILWAUKEE, WISCONSIN, ASSIGNOR TO THE CUTLER-HAMMER MFG. CO., OF MILWAUKEE, WISCONSIN, A CORPORATION OF WISCONSIN.

CIRCUIT-CONTROLLER.

1,296,729.

Specification of Letters Patent. Patented Mar. 11, 1919.

Application filed November 20, 1916. Serial No. 132,349.

To all whom it may concern:

Be it known that I, PAUL H. ZIMMER, a citizen of the United States, residing at Milwaukee, in the county of Milwaukee and 5 State of Wisconsin, have invented new and useful Improvements in Circuit-Controllers, of which the following is a full, clear, concise, and exact description, reference being had to the accompanying drawing, forming 10 a part of this specification.

This invention relates to circuit controllers particularly adapted for starting alternating current motors although not limited to such use.

15 In my prior application, Serial No. 89,809, filed April 8, 1916, there is disclosed a controller wherein the movable contacts have a compound pivotal and sliding movement with respect to certain stationary contacts 20 to progressively establish starting and running connections, the arrangement being such that starting connections are established in an extreme position of the movable contacts and running connections in a position 25 intermediate starting position and off position, whereby the movable contacts are returnable directly from running position to off position and the arrangement also being such as to insure direct movement of the 30 movable contacts from off position to starting position.

The present invention relates to this general type of controller and has among its 35 objects to provide for a compound movement of the movable contacts which will insure the direct movements described, while permitting use of the extreme position of the movable contacts for establishment of running connections and the intermediate 40 position of said contacts for establishment of starting connections.

A further object is to provide a controller of the character specified wherein the movable contacts will be insured firm 45 engagement with their coöperating contacts for establishment of both starting and running connections and yet readily operable manually.

Other objects and advantages of the invention will hereinafter appear.

50 The invention will now be more fully and clearly described in connection with

the accompanying drawing illustrating the preferred embodiment thereof.

In the drawing, 55

Figure 1 is a rear elevation of the switch panel of the controller;

Fig. 2 is a sectional view taken on line 2-2, Fig. 1;

Fig. 3 is a detail view taken on the same 60 section line as Fig. 2, but showing the parts in a different relation, and,

Fig. 4 is a diagrammatic view of the switch mechanism employed to control an A. C. motor through the medium of a transformer. 65

Referring to Figs. 1 to 3, there are illustrated five contact arms 1 to 5 of a well known type mounted in groups upon insulating blocks 6 and 7 in turn fixed to a 70 single supporting plate 8. As best illustrated in Figs. 2 and 3, each of these contact arms has a bearing plate 9, provided with a stud 10, the arm being penetrated by the stud and having a transverse bearing rib 11 on which to fulcrum and further having a spring pressure device 12 to yieldingly hold the same against its bearing plate. These contact arms coöperate respectively with contacts 1^a, 2^a, 3^a-3^b, 4^a-4^b, 80 5^a-5^b, all of said stationary contacts being mounted upon an insulating panel 13. The contacts 1^a to 5^a are arranged in horizontal alinement to be simultaneously engaged by the contacts 1 to 5, while the contacts 3^a, 4^a 85 and 5^a are respectively vertically alined with the contacts 3^b, 4^b and 5^b to be engaged upon rectilinear movement of contact arms 3, 4 and 5 following disengagement of said arms from contacts 1^a to 5^a. 90

The panel 13, as shown in Figs. 2 and 3, is supported upon a frame comprising a plate 14 having rearward extensions 15 and 16 and the plate 8 carrying the movable contacts is pivotally supported upon a carrier 17 slidably mounted upon rods 18 and 19 supported vertically by and between the extensions 15 and 16. The carrier pivotally supports the plate 8 upon a pin 20 and has mounted upon said pin a friction roller 95 20^a adapted to bear against a spring pressed friction plate 21 provided on the rear side of the plate 14. Also, the carrier has an upstanding lug 22 to which are pivoted a

pair of links 23 and 24 (Fig. 1) connected by a pin 25 to a second pair of links 26 and 27, the latter being also connected by a pin 28 to a lug on the contact supporting plate 8, thus forming with the former links a toggle connection between said plate and the carrier. This toggle connection is provided for rocking the contact supporting plate on its pivot relatively to the carrier 10 and is operable for this purpose by a bell crank lever 30 through a link 31, said link being attached to said toggle connection at its breaking point by a pin 25. The toggle connection is, however, provided 15 with a stop pin 32 carried by the links 26 and 27 to abut the links 23 and 24 for preventing locking of said connection by operation of the lever 30 and with a stop pin 33 to limit the downward movement of 20 links 23 and 24. The bell crank lever 30 is pivotally supported upon a bracket 34 fixed to the upper end of the panel and is provided with a return spring 35 biasing the same to release said toggle connection. 25 On the other hand, a retaining magnet 36 is provided to hold lever 30 against the action of spring 35, said magnet being mounted upon the front of panel 13 and having a hooked armature 37 to engage a 30 pin 38 carried by a lug on said lever.

The operation of the switch mechanism is as follows: Movement of the lever 30 to the right exerts through the link 31 a direct pull upon the toggle connection between the 35 contact supporting plate and the sliding carrier. Thus initial movement of the lever 30 inherently tends through straightening of the toggle connection, to rock the contact arms toward the panel and thereby effect 40 abutting engagement of said arms with the contacts 1^a to 5^a. Of course, the pull exerted upon the toggle connection tends to a certain extent to lift the carrier but such tendency is opposed by the weight of the 45 carrier supplemented by the frictional action of roller 20^a and other parts and with a properly designed toggle connection the carrier will be insured against elevation until the contact arms have been firmly engaged with the contacts 1^a to 5^a. Then when such engagement has been effected and the stop 32 has arrested the toggle movement, continued pull by the lever 30 will overcome the friction of the carrier, thereby lifting the 55 same and in consequence moving the contact arms rectilinearly to first disengage contacts 1^a to 5^a and then engage contacts 3^b to 5^b, this being the desired sequence of operation. Conversely, when the carrier is 60 in elevated position and the lever 30 is released the friction of the carrier will hold the same against descent while the spring pressure of the operating lever breaks the toggle connection to rock the contact arms 65 away from the panel 13. Then when the

contact arms are rocked to their limit so that the links 23 and 24 engage the stop pin 33 the spring pressure of the operating member will overcome the friction of the carrier and force the same downwardly to 70 its initial position thereby restoring the contact arms to initial position without re-engagement with any of the stationary contacts.

Referring now to Fig. 4, the same diagrammatically illustrates the contact arms 1 to 5 and their coöperating stationary contacts, a three phase motor M, and transformer windings 40 and 41, said contact arms being coöperable with said stationary contacts as above described to establish power connections for said motor from supply lines L, L' and L² first including the transformer windings and then excluding said windings. More specifically, said contact arms 1, 2 and 5 when in engagement with contacts 1^a, 2^a and 5^a serve to connect the transformer windings 40 and 41 across lines L'—L² and L—L² respectively, while contact arms 3 and 4 when in engagement with contacts 3^a and 4^a serve to connect the left hand and center terminals of the motor to intermediate points on the transformer windings 41 and 40 respectively, the right hand terminal of the motor being permanently connected to one terminal of each of said windings. Then when the contacts 3, 4 and 5 are shifted into engagement with the contacts 3^b, 4^b and 5^b they connect the motor terminals directly to lines L', L² and L². Also, this figure diagrammatically illustrates the retaining magnet 36 as connected across lines L' and L² through contact arms 4 and 5.

It is of course, to be understood that the 105 controller illustrated might be utilized for effecting other circuit variations and might be modified in various ways without departing from the scope of the appended claims.

What I claim as new and desire to secure 110 by Letters Patent is:

1. In a circuit controller, the combination with a plurality of stationary contacts, of a coöperating movable contact element, a slidably mounted member pivotally supporting 115 said movable contact element and means for exerting an operating force upon said movable contact element to first rock the same upon said member to abut one of said stationary contacts and then slide the same 120 through movement of said member to engage another of said contacts.

2. In a circuit controller, the combination with a plurality of stationary contacts, of a coöperating movable contact element, a slidably mounted member pivotally supporting 125 said contact element and means for exerting an operating force upon said movable contact element to first rock the same upon said member to abut one of said stationary con- 130

tacts and then slide the same through movement of said member to engage another of said contacts, said member having means to oppose its sliding movement to provide for 5 the same sequence of pivotal and sliding movements of said contact element in returning to initial position.

3. In a circuit controller, the combination with a plurality of stationary contacts, of a 10 coöperating contact element supported for a pivotal movement to abut one of said contacts and for rectilinear movement to engage another of said contacts and operating means for said contact element including a toggle 15 connection for effecting said movements progressively.

4. In a circuit controller, the combination with a plurality of stationary contacts, of a coöperating contact element supported for 20 a pivotal movement to abut one of said contacts and for rectilinear movement to engage another of said contacts and operating means for said contact element including a toggle connection for effecting said movements 25 progressively, and in the same order for operation of said contact element both to and from a predetermined final position.

5. In a circuit controller, the combination with a plurality of stationary contacts, of a 30 coöperating contact element, a movable member pivotally supporting said contact element for abutment with one of said stationary contacts and movable to slide said contact element relatively to said stationary 35 contacts, a toggle connection between said contact element and said supporting member and an operating member for said contact element acting thereon through said toggle to first move the same pivotally on said member and then slidingly through movement of said member.

6. In a circuit controller, the combination with a plurality of stationary contacts, of a coöperating contact element, a movable 45 member pivotally supporting said contact element for abutment with one of said stationary contacts and movable to slide said contact element relatively to said stationary contacts, a toggle connection between said 50 contact element and said supporting member and an operating member for said contact element acting thereon through said toggle to first move the same pivotally on said member and then slidingly through movement of said member for both final 55 positioning and return of said contact element.

7. In a circuit controller, the combination with a plurality of stationary contacts, of 60 a coöperating movable contact element, a

slidably mounted member pivotally supporting said contact, said member having means for opposing its sliding movement and operating means for said contact element including a toggle connection between 65 the same and said member to initially rock said contact element toward and away from said contacts in response to reverse operating forces and thereafter effect sliding movements of said member in response to a 70 continued operating force in a direction corresponding to that of the operating force.

8. In a circuit controller, the combination with a plurality of stationary contacts, of a coöperating contact element, a bearing 75 member for said element upon which the latter is pivotally supported and biased in one direction, a movable carrier pivotally supporting said bearing member and means for moving said bearing member independently 80 of said carrier and also by movement of the latter to impart a compound pivotal and rectilinear movement to said element for engagement of the latter with said contacts progressively and also for return of said 85 element from final position to initial position.

9. In a circuit controller, the combination with a plurality of stationary contacts, of a coöperating contact element, a bearing 90 member for said element upon which the latter is pivotally supported and biased in one direction, a movable carrier pivotally supporting said bearing member and means including a toggle connection between said 95 bearing member and said carrier for moving said bearing member independently of said carrier and also by movement of the latter to impart a compound pivotal and rectilinear movement to said element for engagement 100 of the latter with said contacts progressively and also for return of said element from final position to initial position.

10. In a circuit controller for alternating current motors, the combination with a plurality of sets of stationary contacts, a plurality of coöperating contact elements, and means supporting said elements for movement together first pivotally to engage certain of said contacts for establishing starting connections and then rectilinearly to engage other of said contacts to establish running connections, said supporting means also providing for return of said elements from final position to initial position without reestablishment of starting connections. 110

In witness whereof, I have hereunto subscribed my name.

PAUL H. ZIMMER.
